(57) **CLAIM**

The ornamental design for a tool handle with storage compartment, as shown and described.

DESCRIPTION

FIG. 1 is a perspective view of the tool handle and the storage compartment of the present invention showing my new design;

FIG. 2 is a front side elevational view thereof;

FIG. 3 is a back side elevational view thereof;

FIG. 4 is a side elevational view thereof;

FIG. 5 is another side elevational view thereof;

FIG. 6 is a top plan view of the handle;

FIG. 7 is a bottom plan view of the handle;

FIG. 8 is a top plan view of the storage compartment;

FIG. 9 is a bottom plan view of the storage compartment; and,

FIG. 10 is a perspective view of the FIG. 1 in an assembled position.

The broken lines form no part of the claimed design.
